(57) **CLAIM**

The ornamental design for a vehicle as shown and described.

DESCRIPTION

FIG. 1 is a side view of a vehicle showing my new design; and,

FIG. 2 is another side view thereof, with components of the design shown in an alternate position.

The broken lines illustrate portions of the vehicle that form no part of the claimed design. The dot-dash lines illustrate the boundary of claimed portions of the vehicle, and the dot-dash lines themselves form no part of the claimed design.
